WILLIAM HALL, JR., OF NORTH ADAMS, MASSACHUSETTS.

Letters Patent No. 90,530, dated May 25, 1869.

SKATING-ROD AND STOOL.

The Schedule referred to in these Letters Patent and making part of the same.

To whom it may concern:

Be it known that I, WILLIAM HALL, Jr., of North Adams, in the county of Berkshire, and State of Massachusetts, have invented a new and useful Improvement in Combined Skating-Rod and Stool; and I do declare that the following is a true and accurate description thereof, reference being had to the accompanying drawings, and to the letters of reference marked thereon, and being a part of this specification.

Figure 1 is a view of my invention, extended for a skating-rod.

Figure 2 is the same, closed for a seat.

Like letters indicate like parts in each figure.

The object of this invention is the construction of a rod to be used in skating, so arranged that when extended it may be used as a balancing-pole, or a skating-rod, and when closed, may be used for a seat.

The rod is made in more or less sections, each enough smaller than the other, and hollow, so that the sections will close in upon each other, telescopically.

A seat is provided and secured properly to one end of the rod, and a strap is so attached as to form a loop, which a novice may grasp, to sustain himself

while receiving instruction in skating, while his instructor grasps the other end of the rod.

A, in the drawings, represents the rod, made in as many hollow sections as may be desired, and so constructed that the sections will slip into each other telescopically.

B is a seat, properly secured to one end of the rod, and may be upholstered, if desired.

C is a strap, secured to the seat to form a loop, as described heretofore.

D is a foot, secured at the opposite end of the rod, and may be provided with a spur or spurs, E, to prevent slipping on the ice.

The operation of this device is so simple, that a description thereof is not deemed necessary.

What I claim as my invention, and desire to secure by Letters Patent, is—

The rod A, when constructed as described, and provided with seat B, strap C, and foot D, and operating substantially as and for the purposes set forth.

WILLIAM HALL, JR.
